(57) **CLAIM**

The ornamental design for a square gear shift cover, as shown and described.

DESCRIPTION

FIG. 1 is a perspective view of a square gear shift cover;

FIG. 2 is a front view of the cover;

FIG. 3 is a rear view of the cover;

FIG. 4 is a left side view of the cover;

FIG. 5 is a right side view of the cover;

FIG. 6 is a top view of the cover; and,

FIG. 7 is a bottom view of the cover.

The broken lines in FIGS. 1-6 depict claimed stitching; the broken line in FIG. 7 defines the claim boundary and forms no part of the claim.
